ABRAHAM GOODMAN, OF NEW YORK, AND JACOB GOODMAN, OF BROOKLYN, NEW YORK

HAIR-ENDS WAVER

Application filed April 26, 1928. Serial No. 272,890.

This invention relates to an improved hair ends waver.

Among the principal objects which the invention has in view are: To provide a tool for curling the ends of hair; to provide means for maintaining the tool on the hair when applied thereto for any desired length of time; to simplify and improve the construction.

Other objects, desirable features and advantages of the invention will appear as the description proceeds.

In the drawings:

Figure 1 is a side elevational view of a hair ends waver constructed in accordance with the present invention, showing alternative positions of the parts in dotted lines;

Figure 2 is a plan view of the hair waver with the parts in the position assumed when the hair waver is applied to the hair;

Figure 3 is an end view of the hair waver looking from the left as in Figure 2;

Figure 4 is a cross-sectional view taken as on the line 4-4 of Figure 2;

Figure 5 is a sectional view taken as on the line 5-5 of Figure 2.

Referring now more particularly to the drawings which show by way of illustration and example the preferred embodiment of the invention and to the details of which the invention is not to be considered confined, the waver comprises a rod element 10 with which is associated another element 11, the elements 10 and 11 being pivoted together as at 12. The elements are preferably constructed of sheet metal fashioned into the shapes desired. The material which is most desirable for the purpose is aluminum, because of its weight and cheapness. The element 11 has a semi-circular cross-section as shown in Figure 4 so as to closely embrace the side of the rodlike element 10 against which it is normally disposed for a major portion of its length. The elements 10 and 11 also have off-set portions or lugs 13 and 14 for the pivot. From Figure 1 it will be seen that the pivot is located be-

tween the ends of the elements 10 and 11 and at unequal distances therefrom so as to provide a short finger grip portion 15 and a relatively longer hair gripping portion 16. A leaf spring 17 is disposed within the finger grip portion and cooperates with the finger grip ends and with the elements 10 and 11 in such a way as to urge the elements together on the hair.

The pivot is provided by inturned ends 19 of a loop of wire 18 which has sides extending lengthwise of the elements 10 and 11 and at spaced distances therefrom and an end portion 20 which as indicated in Figure 3 is adapted to snap into the groove 21 on the end of the rod element 10 and to be resiliently and detachably locked in said groove. The side portions of the wire are preferably bowed outwardly to some extent as shown in Figure 2.

In operation, the finger grip portions 15 of the elements 10 and 11 are squeezed together against action of the spring 17 so that the hair gripping portions of the elements separate as indicated in dotted lines in Figure 1. The ends of the hair are then arranged uniformly over the rod like element 10 and between said element and the cooperating element 11, after which the finger grip portions are released and the hair gripping portions urged together by the action of spring to tightly and uniformly engage the hair therebetween, the hair being caused to assume a wave when forced around the rod element by the cooperating element 11. During this initial positioning of the hair, the wire element or loop 18 is swung so as to assume a position shown by dotted lines in Fig. 1 of the drawings on the same side as the finger grip portion of the waver and not to interfere while placing the hair in the waver. This loop in this position constitutes a handle with which the tool is rotated, and to this end is preferably held in the palm of the hand while the fingers engage the fin-

ger grip portions 15 of the tool to open up the waver for the insertion of the hair. After the ends of the hair have been gripped between the elements 10 and 11, the hair is wound upon said elements using the loop 18 for this purpose, and after a sufficient amount of hair has been wound thereon, the loop 18 is swung back and over the tool and hair until the end portion 20 thereof comes into resilient locking engagement with the groove 21 and is locked in position. The hair upon the waver is now disposed around the elements 10 and 11, with its ends gripped between said elements and the hair clamped 15 snugly on the periphery thereof between the side portions of the wire loop and said periphery.

The hair is thus retained curled around the tool by the loop of wire 18 and may remain for sufficient time to impart a lasting wave or curl to the ends of the hair. In removing the hair waver from the hair, it is only necessary to swing back the wire loop 18 thereby releasing the hair curled around the waver, and to open the waver and withdraw it from the hair.

Claims:

1. A hair waver of the class described, comprising two cooperating elements, a loop 30 of wire between which said elements are disposed for the major portion of their length, said loop of wire having inturned ends forming a pivot for said elements, and sides extending lengthwise and spaced from said elements, and an end adapted to resiliently and

35 detachably interlock with the end of one of said elements, said loop of wire being in a plane which substantially intersects the axis of the element with which it interlocks, in their locked position.

2. A hair waver of the class described, comprising two cooperating elements, a loop of wire between which said elements are disposed for the major portion of their length, 45 said loop of wire having inturned ends forming a pivot for said elements, and sides extending lengthwise and spaced from said elements, and an end adapted to resiliently and detachably interlock with the end of one of 50 said elements, and resilient means acting to urge said elements together on the hair winding side of the pivot, said loop of wire being in a plane which substantially intersects the axis of the element with which it interlocks, 55 in their locked position.

3. A hair waver of the class described comprising two cooperative pivoted elements between which the ends of the hair are adapted to be clamped and on which the hair is 60 adapted to be wound, one of said elements having a substantially circular cross section throughout the major portion of its length and the other of said elements having a curved cross section so as to closely embrace 65 the first element throughout the major por-

tions of its length in the closed position of said elements, a loop of wire between which said elements are disposed for the major portion of their length, said loop of wire having internal ends forming a pivot for said elements and sides extending lengthwise and spaced from said elements and outwardly bowed therefrom and an end adapted to resiliently and detachably interlock with the end of the element of circular cross-section 75 in their locked position.
